UNITED STATES PATENT OFFICE

161,654

DOOR HINGE

John M. Scovill, Seattle, Wash.

Application December 19, 1949, Serial No. 6,710

Term of patent 7 years

(Cl. D10—9)

To all whom it may concern:

Be it known that I, John M. Scovill, a citizen of the United States, residing at Seattle, State of Washington, have invented a new, original, and ornamental Design for Door Hinges, of which the following is a specification, reference being had to the accompanying drawing, forming a part hereof.

Figure 1 is a plan view of a door hinge, showing my new design;

Fig. 2 is a front elevation thereof, and

Fig. 3 is a side elevation of the same.

I claim:

The ornamental design for a door hinge, as shown.

JOHN M. SCOVILL.
